United States Patent Office

Des. 184,771
Patented Mar. 31, 1959

184,771

DRAWING GUIDE

Walter J. Sharrock, Upper Arlington, Ohio, assignor to American Brake Shoe Company, New York, N.Y., a corporation of Delaware

Application November 18, 1957, Serial No. 48,497

Term of patent 14 years

(Cl. D52—1)

Fig. 1

Fig. 2

Fig. 1 is a plan view of a drawing guide embodying my new design; and

Fig. 2 is an edge view of the drawing guide seen in Fig. 1.

I claim:

The ornamental design for a drawing guide, as shown.
